UNITED STATES PATENT OFFICE

AUGUSTINUS EDVARD JONSSON, OF DALTORP, LIDINGO, SWEDEN

STRAINING ARRANGEMENT IN VACUUM DRYING APPARATUS

Application filed September 9, 1931, Serial No. 561,844, and in Sweden September 25, 1930.

The present invention relates to an arrangement in such strainers adapted for vacuum drying-apparatus having a rotating or oscillating drying-drum as consist of a hollow body located in the drying-drum and having one end closed, said hollow body having its circumference or part of it provided with straining slots. Further, said arrangement possesses a cleansing-device adapted to automatically remove impurities, dust or the like emanating from the mass that may have entered said slots of the hollow body. This cleansing-device is shaped as a holder mounted to rotate in relation to the hollow body and eccentrically weighted. Said holder is, further, provided with cleansing teeth or projections corresponding to the number of the slots and extending into the latter. At the rotation of the drum and, thus, of the hollow body, said teeth are displaced in said slots.

In such straining arrangements it has, however, been found that the impurities, which have entered the straining slots, are not entirely removed at the displacement of the cleansing-teeth in the slots, as said impurities are forced, by the cleansing-teeth, towards the ends of the slots. On account of this fact the impurities are, more and more, pressed together in the slots, which finally will, by this fact, be completely stopped up.

To avoid this inconvenience, according to this invention, the hollow body is, at the ends of the straining slots, provided with recesses running radially inwards. In the sides of these recesses the straining slots are cut down to a depth somewhat larger than that which corresponds to the height of the cleansing teeth extending into the straining slots so as to allow said teeth, when going into said recesses, to push out the impurities gathered in the slots.

The annexed drawing shows an embodiment of the arrangement according to the invention.

Fig. 1 is a longitudinal section through the arrangement on the line I—I in Fig. 2. Fig. 2 is a cross-section on the line II—II in Fig. 1.

Referring to the drawing, 1 is an end wall 50 of the drying-drum at which the hollow body

or the holder 3 of the tubular piece 2 are attached, for instance by means of bolts 4. That end of the tubular piece that is connected with the holder is open, as shown, the opposite end of the tubular piece being closed by means of a wall 5 connected with the tubular piece 2. Said wall 5 has its center provided with a recess adapted to receive a pin 7 arranged on a bracket 6. The tubular piece 2 is provided with straining slots 8 running peripherally and extending along parts of the circumference of the tubular piece. Two rings 9 are arranged at the ends of the tubular piece 2, which rings are mounted to turn on the tubular piece. 55 60 65

Further, said rings are interconnected by a suitable number of cross-bars 10 being provided with a number of cleansing-teeth 11 corresponding to the number of the straining slots. The cleansing-teeth 11 extend into the straining slots 8 and are adapted to be displaced in said slots at the rotation or oscillation of the drum. To this purpose, a projection 12 extends from each ring 9, said projections 12 together carrying a weight 13 attached by means of bolts 14. 70 75

When the tubular piece 2 is put into communication with the source of vacuum, the vapors and gases, produced in the drying-drum, are sucked off through the straining slots 8 of the tubular piece and are removed in a suitable way. At this occasion, a part of the impurities, dust or the like emanating from the mass to be dried will, however, easily enter the straining-slots so that the latter will run risk of being stopped up. However, by rotating the drying-drum, the cleansing-teeth 11 are, by the influence of the weighted holder 12, 13, imparted a movement relatively to the slots, thus causing them to be 80 85 90 95 cleansed.

It may be suitable to arrange the working surfaces of the cleansing-teeth 11 in such a way as shown in Fig. 2, that-is-to-say, obliquely. By this fact, the cleansing-teeth, at the same time as they displace, peripherally, the matter located in the slots, they will also force it to move radially outwards.

The above-described straining device is in its main features already disclosed in my 100

Patent No. 1,748,955. As mentioned above it has been found that there is a tendency of the cleansing-teeth packing together, gathering impurities at the end of the straining slots, thus gradually clogging them. To avoid this inconvenience, I have, according to the present invention, provided recesses 15 in the outer surface of the tubular piece 2, said recesses running continuously in the longitudinal direction of the tubular piece and in a transverse direction to the straining slots which extend to and communicate with the recesses 15 in such a way that the cleansing-teeth during the above described relative motion can enter into said recesses, thus pushing before them and into said recesses any gathering impurities that otherwise would tend to accumulate at the ends of the straining slots. To facilitate said entrance of the cleansing-teeth into the recesses 15, the slots 8 are cut down in the walls of the recesses to a depth somewhat larger than that which corresponds to the height of the cleansing-teeth extending into the straining slots.

As illustrated in the lower part of Fig. 1, the recesses 15 are in substantially their entire length open towards the interior of the drying drum forming longitudinal pockets with the bottom 16, whereby any impurities pushed into them by the cleansing-teeth in the described way will automatically drop off during the rotating or oscillating motion of the drying drum.

The device described and illustrated is to be considered only as an embodiment, and the invention may also be applied in many other ways without departing from the scope of the invention.

Having now particularly described the nature of my invention and the manner of its operation, what I claim is:

1. In vacuum drying apparatus provided with a rotatable drying drum a straining device comprising a hollow body arranged in said drying drum and connected with a source of vacuum, straining slots provided on the circumference of said hollow body, cleansing-teeth projecting into said straining slots, means for imparting a relative motion between said teeth and said slots in the longitudinal direction of the latter so as to remove impurities tending to gather in said slots, and recesses provided in the surface of said hollow body running continuously in a transverse direction to said straining slots and communicating with the latter in such a way that said cleansing-teeth can enter into said recesses and thus cleanse the straining slots.

2. In vacuum drying apparatus provided with a rotatable drying drum a straining device comprising a hollow body arranged in said drying drum and connected with a source of vacuum, straining slots provided on the circumference of said hollow body, cleansing-teeth projecting into said straining slots, means for imparting a relative motion between said teeth and said slots in the longitudinal direction of the latter so as to remove impurities tending to gather in said slots, recesses provided in the surface of said hollow body running continuously in a transverse direction to said straining slots and communicating with the straining slots as well as with the interior of the drying drum, said communications being so adapted that the cleansing-teeth can enter into said recesses thereby cleansing the straining slots and that impurities pushed into the recesses by the cleansing-teeth will automatically drop off.

AUGUSTINUS EDWARD JONSSON.
